Fred Adrian Truesdell

UNITED STATES PATENT OFFICE.

FRED ADRIAN TRUESDELL, OF YOUNGSTOWN, OHIO.

ROTARY VALVE FOR INTERNAL-COMBUSTION ENGINES.

1,175,202.

Specification of Letters Patent. Patented Mar. 14, 1916.

Application filed July 12, 1915. Serial No. 39,349.

To all whom it may concern:

Be it known that I, FRED ADRIAN TRUESDELL, residing in Youngstown, in the county of Mahoning and the State of Ohio, have made new and useful improvements on my own invention of Rotary Valves for Internal-Combustion Engines, of which the following is a specification, reference being had to the accompanying drawings.

10 This invention relates to an improved method of applying, oiling, and adapting said rotary valves to an internal combustion motor, of one or more cylinders.

15 Another and more specific object of the improvement resides in the provision of a means of removing the valves for inspection without disturbing the timing gears rotating said valves, also the provision of an automatic wear compensating gear or spring, 20 for automatically taking up the wear that may occur between the valve and its seat.

25 The improved invention has for still another object in providing a floating valve or valve stem, working in conjunction with a loose key. An automatic wear compensating spring and a valve driving gear set in ball bearings to eliminate side thrust on the valve stem, necessarily due to the operation of the driving gears.

30 With the above objects in view the improved invention consists in certain construction, combination and arrangements of the parts which I shall hereinafter fully describe and claim.

35 For fully understanding the improved invention, reference is to be had to the following and accompanying drawings in which,

Figure 1, is a vertical section through the end of one of a pair of detachable cylinder heads showing the old arrangement of valves and gear driving mechanism. Fig. 2, is the intake side of a set of my new improved cast *en bloc* detachable cylinder heads showing connections for intake and water manifolds, 40 also, oil guards around valve driving mechanism with one of the guard covers removed. Fig. 3, is a vertical section in part taken at line A of Fig. 2 across the end of a set of cast *en bloc* cylinder heads showing the arrangement of driving gear oiling system and floating rotary valve in conjunction with the automatic wear compensating spring.

45 Referring in detail to the drawings as shown, Fig. 1, is a vertical section taken through the end of a pair of ordinary de-

tachable cylinder heads showing the old arrangement of a valve therein.

Fig. 2, is my improved cylinder head construction preferably cast *en bloc* of which 27 designates the exhaust water ports or openings to which the manifold is connected, 15, designates the intake ports or openings to which the intake manifold is connected. 52, designates the studs or cap screws which hold the detachable heads to the cylinder. 6, designates the crankshaft of the engine which operates shaft 13 through the medium of chain 20 operating over suitable gears carried by crank shaft 6 and gear shaft 70 13. 28 which is part of the main casting 4, designates the oil guards, one of which encloses each valve stem and its operating mechanism. 29, designates the caps which hold shaft 13 in its bearings. 30, the cap 75 screws which secure caps 29.

As shown in Fig. 3, each cylinder is provided with a valve plate or disk 8, the stem of which is 10 and runs through opening 11, in the cylinder head and through gear 12, which is firmly held to its proper place on ball bearings 32, which operate against ball cup 31, and hollow cone 33, which screws through cast arm 34, which is part of the main casting 4, and the oil guard 80 28. Cone 33 being fitted with slots or notches 35 on its outer surface into which fits set screw 36 which is arranged in the outer end of arm 34, the object of the set screw is to lock the cone 33 after it has been 90 properly adjusted.

Valve stem 10 and gear 12 are fitted with key ways 37 and 38 into which slips loose key 39, on top of which rests heavy spring 40, which is held in place by a special nut 95 41, secured on the upper end of valve 10, therefore making a floating valve with an automatic wear compensator, and any wear that may occur between the valve plate 8, and its seat 7, will be readily and automatically taken care of by spring 40, which rests on top of gear 12 and pushes against special nut 41, on valve stem 10, therefore pulling the valve plate 8 tightly against its seat 7.

42, designates a force feed oil pipe coming 105 from any suitable force feed oiler, not shown. Pipe 42 is fastened to oil nozzle 44 by means of nut 43. Nozzle 44 being securely fastened to arm 45 which is held to cast arm 34 by means of cap screw 46, therefore arm 45 keeps nozzle 44 from turning with valve stem 10, nozzle 44 delivers oil 110

into central bore 23, leading to absorbent material 25, fastened in the face of the valve plate 8, the surplus lubricant not used by absorbent material 25 escapes through bore 26, in the valve stem 10, into oil guard 28, thoroughly lubricating gears 12 and 14, and the surplus in the oil guard 28 is allowed to drain back to the source of supply, not shown, through drain pipe 47 which is substantially placed at sufficient height to insure good lubrication to the valve operating mechanism. 49, designates a detachable cover to protect the gears and keep the lubricant from being wasted. 50, designates a clamp bar and bolt, partly shown. 51 a thumb nut on 50. The object of 50 and 51 is to secure cover 49, to oil guard 28. 9, designates the opening or port in the valve plate which registers with intake and exhaust ports, not shown, in each rotation of the valve. 16, designates an individual exhaust provided for each cylinder. 25 From the foregoing description taken in connection with the accompanying drawings it is thought that the construction and means of operation of my improved invention will be clearly and fully understood. 30 Be it also hereby understood that I have used many forms of automatic wear-compensating arrangements, and found most of them equally successful, also, that said valves operate very well without an automatic compensating gear of any description. 35

Let it also be understood that I know of springs having been used to retain rotary valves against their seats but I do not know of springs ever having been used above the driving gear for a wear compensator as I have used the same. It will also be readily seen by a careful study of the drawings. Should a valve stem break the valve would not drop into the cylinder causing further breakage of the engine. Therefore this improvement is also susceptible of many minor modifications in form and arrangement of the parts and I therefore reserve the privilege of resorting to all such legitimate changes as may be fairly embodied within the spirit and scope of the appended claim.

Having described my improvement what I claim is:

The combination in an engine having a combustion chamber with a rotary valve engaged on a seat provided in the head of said chamber the stem of said valve extending through a bore in the cylinder head and through a driving gear set in bearings, a spring engaged between said driving gear and a collar attached to the valve stem, an absorbent material arranged in the face of said valve and a means of supplying a lubricant to said absorbent material.

In testimony whereof I hereunto affix my signature in the presence of two witnesses.

FRED ADRIAN TRUESDELL.

Witnesses:

CLARA HUBLER,
B. K. DE CAMP.
